Primary Examiner—Raphael Barkai[57] **CLAIM**

The ornamental design for a skate wheel hub, as shown and described.

DESCRIPTION

FIG. 1 is a perspective view of my improved skate wheel hub showing my new design;

FIG. 2 is a front elevational view thereof, the rear elevational view being identical; and,

FIG. 3 is a top plan view thereof, the bottom plan and the left and right elevational views are identical.

1 Claim, 1 Drawing Sheet Fig. 1.

Fig. 2.
